CLAIM

The ornamental design for garden trowel, as shown and described.

DESCRIPTION

FIG. 1 is a front elevational view of the garden trowel of this design's first embodiment;

FIG. 2 is a rear elevational thereof;

FIG. 3 is a right side elevational view of the first embodiment of the garden trowel of this design.

FIG. 4 is a bottom plan view of this first embodiment of a garden trowel.

FIG. 5 is a top plan view thereof;

FIG. 6 is a front elevational view of the garden trowel of this design's second embodiment;

FIG. 7 is a rear elevational thereof;

FIG. 8 is a right side elevational view of the second embodiment of the garden trowel of this design.

FIG. 9 is a bottom plan view of this second embodiment of a garden trowel; and,

FIG. 10 is a top plan view thereof.

The bunny-shaped handle shown in dashed lines is but an exemplary handle and forms no part of this design.
